UNITED STATES PATENT OFFICE.

STERLING ELLIOTT, OF NEWTON, MASSACHUSETTS.

APPARATUS FOR MOISTENING STENCIL-BLANKS.

1,210,441.

Specification of Letters Patent. Patented Jan. 2, 1917.

Application filed September 16, 1915. Serial No. 51,096.

To all whom it may concern:

Be it known that I, STERLING ELLIOTT, a citizen of the United States, residing at Newton, in the county of Middlesex and State of Massachusetts, have invented an Improvement in Apparatus for Moistening Stencil-Blanks, of which the following is a specification.

Stencils adapted to be used in addressing-machines and having stencil-sheets, or portions, composed of mimeograph paper or the like, must be in a moist condition when embossed or printed by a typewriting machine, so that the impact of the type will not break the paper. Usually the stencil-blanks are moistened by a brush which has been dipped in water. The brush method consumes considerable time, as each stencil-blank must be separately moistened, and then the moistened stencil-blanks are taken separately by the operator and placed in the typewriting machine to have an address or other matter embossed or printed, so to speak, thereon. Furthermore, this method of moistening is exceedingly unsatisfactory, for the reason that the amount of water applied is frequently more than is necessary, which results in wetting the type and adjacent parts of the type-writing-machine, causing them to rust.

This invention has for its object the construction of an apparatus especially adapted for moistening stencil-blanks, it comprising moistening-means for the stencil-blanks, and feeding-means for feeding the stencil-blanks *seriatim* from a pile to the moistening-means and for then delivering them upon a shelf, or other element, whereby they may be readily grasped by the operator and placed in the typewriting-machine, and operating-means for said feeding and moistening-means having a handle or equivalent member, so arranged that by a simple turn of the handle, all the motions may be performed to deliver a moistened stencil-blank into a position whereby it is readily accessible.

Figure 1 is a side elevation of a stencil-blank moistening and delivering-device embodying this invention. Fig. 2 is a plan view of the same. Fig. 3 is a longitudinal vertical section. Fig. 4 is a transverse section through the stencil-blank receptacle and moistening-device. Fig. 5 is an enlarged longitudinal vertical section of an essential portion of the moistening-device,

and, Fig. 6 is a sectional detail showing an end-view of the moistening-device.

The main frame-work 1 has a table 2 with a flat top. On said table a pair of guiding and supporting elements for the stencil-blanks are arranged, said elements being made as opposites and designated at 4 and 5. Each said element has a pair of lips arranged with a narrow space between them to form a guide-way for the stencil-blanks, and said elements are arranged on the table, in a horizontal plane, and disposed to receive the stencil-blanks between them with the ends of the blank arranged in and free to move along the guide-way formed by them, the stencil-blanks resting on the lower lips. Superimposed on each said element is an upright end-guide 6, said guides being made substantially alike but as opposites, and having a channel in one side, and said end-guides are arranged with their channels facing each other. The upper lips of the guiding and supporting elements are cut away coextensive with the channels of the end-guides to admit of a pile of stencil-blanks which are arranged between said guides and in the channels thereof to rest on the lower lips of the guiding and supporting elements, in order that the lowermost stencil-blank of the pile may be removed from the bottom of the pile and moved along the guide-ways of the guiding and supporting elements. A sliding-pusher is provided for moving the stencil-blanks forward, one at a time, which is here shown in Fig. 2 as a plate 8, having its forward edge recessed to form a pair of stencil-blank engaging-portions 9, or in lieu thereof, to otherwise form an engaging-portion. The sliding-pusher is made of a width substantially equal to the length of the stencil-blank. The plate 8 is secured to the top of a block 12, which is supported on a horizontally disposed sliding-bar 13, arranged in bearings beneath the table. A pin 14 extends downward from the block 12, to which is loosely connected one end of a link 15, the other end of which link is connected to the extremity of one arm 16, of a bell-crank lever, pivoted at 17, the other arm 18 of which lever has connected with it, by a universal-joint, one end of a link 19, the other end of which link is connected by a universal-joint with a crank-arm 20, arranged on a shaft 21, having its bearings in the frame-work and to which a hand-crank 22 is secured.

The hand-crank 22 is adapted, upon each complete rotation, to move the sliding-pusher forward a distance equal to the width of a stencil-blank, and to return the same to its normal position preparatory to engaging the next stencil-blank of the pile. In lieu of this form of feeding-means for the stencil-blanks, other forms may be employed adapted to feed forward the stencil-blanks one at a time. The stencil-blank, which is fed forward by the pusher, is moved into position for engagement with moistening-means, arranged directly in front of the pile of stencil-blanks. The moistening-means, here shown, consists of an endless-band 25 of some water-absorbing material, extended over the table and down into a water-containing receptacle 26. The under part of that portion of the band which is arranged above the table moves over a plate 27, set in a recess in the top of the table and beneath the forward end-portions of the guiding and supporting elements 4 and 5, so that that portion of the band between the elements 4 and 5 is arranged beneath a stencil-blank, which has been fed forward by the feeding-means. The plate 27 may have a raised or thickened portion 28, along that portion thereof, between the elements 4 and 5, by which the band is raised at such place to bring it very close to the underside of the stencil-blank. The upper part of that portion of the band which is arranged above the table extends over the tops of said elements 4 and 5. One end of the endless-band passes over an idle-roll 30 journaled in a bracket 31, secured to one end of the main-frame at the side of the element 4. At the opposite end of the table an intermediate portion of the endless-band passes over two rolls 35 and 36, arranged side by side and close together, the upper part of the band passing over the roll 35, and the under part passing over the roll 36, and by the close association of the two rolls said under part is engaged by both rolls and is thereby pressed as the rolls rotate to squeeze out the surplus water from the band. The other end of the endless-band extends downward from said rolls 35, 36, and passes around a roll 38, arranged in the water-containing receptacle 26, near the bottom thereof, so that the band which passes over said roll is submerged in the water. The lower roll 38 over which the end of the band passes, is arranged for adjustment, whereby the endless-band may be tightened, and, as here shown, said roll has its journals arranged in vertical slots 39 of its supporting-frame, and a yoke 40 is pivotally connected to said frame at 41, the arms of which extend over the journals of said roll 38, and by depressing said yoke, said roll is forced downward to tighten the endless-band. As here shown the crown of the yoke has a set-

screw 42 which is arranged to occupy a position in any part of a slot 43, in a curved arm 44, which is pivotally secured to the frame. This form of tightening-means is simple and effective, yet my invention is not limited to the use of tightening-means of this particular structure. 70

One of the squeezing-rolls, as 35, serves as the driving-roll for the endless-band, and is here shown as having secured to its shaft a mutilated gear 50, which is arranged for engagement with another mutilated gear 51, secured to the hand-crank shaft 21. Upon each rotation of said hand-crank shaft, the driving-roll 35 for the endless-band is turned 75 a part of a revolution, here shown as a third of a revolution, which is sufficient to bring a fresh or moist portion of the band in position for engaging a stencil-blank. 80

As the endless-band is arranged to extend 85 over and under the stencil-blank, it is only necessary to depress the upper part of said band or deflect it to cause the band to engage both the upper and under sides of the stencil-blank, and thereby apply moisture to 90 both faces thereof. To accomplish this result a pressure-plate 55 is arranged for movement up and down above the endless-band, at the stencil-moistening portion of the table, and, as here shown, said pressure-plate is pivotally supported at one end of a lever 56, pivoted at 57, the other end of said lever bearing a roll 58 for engagement with a cam 59, which is secured to the hand-crank shaft 21 of the machine, said cam 100 being arranged to move the pressure-plate downward, and permit of the return of same to normal position on each complete rotation of the shaft. As the pressure-plate is depressed by the cam, the upper part of the 105 band above the stencil-blank is depressed and caused to engage the blank and press it down onto the under part of the band, thereby applying an adequate amount of moisture to both its upper and under faces. The 110 band is held quite taut by the tightening-means, so that when the acting portion of the cam passes by the roll 58, the relaxation of the band is sufficient to lift the pressure-plate and hold it in elevated position. 115

A shaft 60 is attached to the forward edge of the table directly in front of the moistening-means, its upper surface being flush with the surface thereof, so that the stencil-blanks may be freely moved from the moistening-position onto said shelf. Such movement may be imparted to the stencil-blank by the aforesaid feeding-device including the sliding-pusher, which, when engaging the lowermost stencil-blank of the pile and 120 moving it forward causes said blank to move forward the blank ahead of it, and which is in position to be acted upon by the moistening-device to push it forward onto the shelf. Said shelf is entirely exposed and 125 130

is made large enough to receive upon it a stencil-blank in a substantially entirely exposed position, and is easily accessible so as to be grasped by the operator and placed 5 immediately in the typewriting-machine. This means for receiving the moistened stencil-blanks, when discharged from the moistening-device, is simple and effective, but in lieu thereof other receiving-means for the 10 moistened stencil may be provided without departing from my invention.

It will be noted that both the sliding-pusher and the pressure-plate are operated by the hand-crank shaft, and that the sliding-pusher is moved forward while the pressure-plate is reposing in elevated position, and is moved rearward while the pressure-plate is pressed downward into engagement with the endless-band. Furthermore, by a 15 simple turning movement of the hand-crank the stencil-blank is moved forward a distance substantially equal to its width, so that at each turning movement a moistened blank is delivered to and left reposing on 20 the shelf, ready to be grasped by the operator.

The feature here shown, of a pusher arranged to remove the lowermost stencil from the pile, in such manner as to turn it with respect to the stencil blanks above it, forms the 30 subject-matter of my application #82,317, filed March 6, 1916.

I claim:

1. In an apparatus of the kind described, 35 the combination of a receptacle for a pile of stencil-blanks, guiding and supporting-means for the stencil-blanks, moistening-means arranged for engagement with both the upper and under sides of the blank, including a presser, means to operate the presser, receiving-means for the moistened stencil-blanks, and a feeding-device for feeding the blanks successively from the receptacle to the moistening-means, and thence 40 to the receiving-means, said device being operatively connected with the means to operate the presser.

2. In an apparatus of the kind described, 50 the combination of guiding and supporting-means for the stencil-blanks, water-absorbing means arranged above and below the stencil-blank held thereby, and means to press said water-absorbing means into engagement with the stencil-blank.

55 3. In an apparatus of the kind described, the combination of guiding and supporting-means for the stencil-blanks, water-absorbing means arranged above and below the stencil-blank held thereby, and means to 60 press said water-absorbing means into engagement with the stencil-blank, a reservoir associated with said water-absorbing means, and intermittently operated means to move said water-absorbing means.

65 4. In an apparatus of the kind described,

the combination of guiding and supporting-means for the stencil-blanks, an endless water-absorbing band arranged to extend over and under said means, thereby to engage a stencil-blank upon both its upper and 70 under sides, and means for moving said band, and means for applying pressure to said band at a predetermined portion thereof, to press the band into engagement with the stencil-blank. 75

5. In an apparatus of the kind described, the combination of guiding and supporting-means for the stencil-blanks, an endless water-absorbing band arranged to extend over and under said means, thereby to engage a stencil-blank upon both its upper and 80 under sides, and means for moving said band, and means for applying pressure to said band at a predetermined portion thereof, to press the band into engagement with 85 the stencil-blank, and a reservoir associated with said band.

6. In an apparatus of the kind described, the combination of guiding and supporting-means for the stencil-blanks, an endless water-absorbing band arranged to extend over and under said means, thereby to engage a stencil-blank upon both its upper and 90 under sides, and means for moving said band, and means for applying pressure to said band at a predetermined portion thereof, to press the band into engagement with the stencil-blank, a reservoir and a pair of squeezing-rolls associated with said band. 95

7. In an apparatus of the kind described, 100 the combination of guiding and supporting-means for the stencil-blanks, an endless water-absorbing band arranged to extend over and under said means, thereby to engage a stencil-blank upon both its upper and 105 under sides, and means for moving said band, and means for applying pressure to said band at a predetermined portion thereof, to press the band into engagement with the stencil-blank, and an operating-shaft to 110 which the pressure-applying means is connected.

8. In an apparatus of the kind described, the combination of guiding and supporting-means for the stencil-blanks, an endless 115 water-absorbing band arranged to extend over and under said means, thereby to engage a stencil-blank upon both its upper and under sides, and means for moving said band, a pressure-plate for engagement with 120 a portion of said band, and means including a cam for moving said plate to press the band into engagement with the stencil-blank, said plate being elevated by the return movement of said band to normal. 125

9. In an apparatus of the kind described, the combination of guiding and supporting-means for the stencil-blanks, an endless water-absorbing band arranged to extend over and under said means, thereby to engage 130

a stencil-blank upon both its upper and under sides, rolls supporting said band including a pair of squeezing-rolls, one of which serves as a driving-roll for moving 5 the band and mutilated gears arranged on said rolls.

10. In an apparatus of the kind described, the combination of guiding and supporting means for the stencil-blanks, an endless water-absorbing band arranged to extend over and under said means, thereby to engage a stencil-blank upon both its upper and under sides, rolls supporting said band including a pair of squeezing-rolls, one of 15 which serves as a driving-roll for moving the band, and another is arranged to submerge a portion of the band in water, and adjusting-means for said submerging-roll.

11. In an apparatus of the kind described, 20 the combination of a receptacle for a pile of stencil-blanks, guiding and supporting means for the stencil-blanks associated

therewith and extended therefrom, an endless water-absorbing band arranged to extend over and under said means for engagement with a stencil-blank which is held thereby, means for moving said band, and means for applying pressure to said band at a portion thereof to apply moisture to both the upper and under sides of the blanks, a 25 feeding-device for feeding the stencil-blanks from the receptacle into position for engagement with the endless-band, and an operating-shaft to which the feeding-device the moving-means for the endless-band, and the 30 pressure-applying means are connected.

In testimony whereof, I have signed my name to this specification in the presence of two subscribing witnesses.

STERLING ELLIOTT.
